(57) **CLAIM**

The ornamental design for a body temperature screening control unit, as shown and described.

DESCRIPTION

FIG. 1 is a front perspective view of another embodiment of the body temperature screening control unit;
FIG. 2 is a rear perspective view thereof;
FIG. 3 is a top plan view thereof;
FIG. 4 is a front elevation view thereof;
FIG. 5 is a left side elevation view thereof;
FIG. 6 is a right side elevation view thereof;
FIG. 7 is a rear elevation view thereof; and,
FIG. 8 is a bottom plan view thereof.

The broken lines in the figures depict portions of the body temperature screening control unit that form no part of the claimed design.

It will be understood that all lines, including broken and solid lines, are intended to convey the full disclosure and variations of the design and such variations shall be understood to be fully described herein. It will also be understood that any and all broken lines may be converted to solid lines, any and all solid lines converted to broken lines, whether in subsequent division or continuation applications and/or by amendment.
